WATER-COOLING ATTACHMENT FOR
PROJECTION ARC LAMPS

Harold I. Huff, Los Angeles, Calif.

Application October 12, 1948, Serial No. 54,047

5 Claims. (Cl. 176—120)

1

This invention relates to arc lamps for motion picture projectors and the like, and is particularly useful in projector arc lamps of the reflector type although it is not necessarily limited to use with reflector lamps.

An object of the invention is to improve the illumination produced by a projector arc lamp.

Another object is to reduce the rate of carbon consumption without reducing the light.

Another object is to control the direction of the flame or tail of the arc so as to prevent injury to the reflector in a reflector type lamp.

Still other more specific objects are: to reduce flicker; to reduce ash deposit within the lamp housing; to prevent color production and maintain a pure white light on the screen; to eliminate need of using metallic coated carbons; to maintain constant resistance in the arc circuit, which keeps the current constant and maintains a uniform crater in the positive carbon; to burn the metal clean when using metallic coated carbons; to produce a relatively deep crater in the positive carbon and thereby reduce the flame from the arc; to reduce heat waves in the lamp house in the path of the light; to enable increasing the current and thereby increasing the light intensity obtainable with carbons of any given size.

Other specific objects and features of the invention will become apparent from the description to follow of a particular embodiment of the invention.

Broadly, the present invention consists of water cooled apparatus for cooling and conducting current to the positive carbon of a projection arc lamp at a point thereon closely adjacent to and at a constant distance from the arc. The cooling of the carbons closely adjacent the arc has the direct advantages of increasing the depth of the crater in the positive carbon, and causing the metal of a metallic coated carbon to burn clean. It also has the advantage of permitting conduction of the current to the carbon at a point thereon spaced a short, constant distance from the arc, which results in the indirect advantages of: eliminating necessity of using metal coated carbons; maintaining constant resistance in the arc circuit; enabling the use of heavier currents in carbons of given size; and facilitating the automatic feeding of the carbons in proper relation to maintain exact focus.

The invention also permits the use of larger carbons with the same current while producing the same light intensity, under which conditions it has the advantage of greatly increasing carbon life. Thus with the present invention, 70 amperes

2

of current with a 9 millimeter carbon gives the same light on the screen as 70 amperes through an 8 millimeter carbon with prior projectors, and the 9 millimeter carbon, when used with my attachment, will last twice as long as the 8 millimeter carbon in the conventional lamp.

The production of ash deposit on surfaces within the lamp housing is reduced, by use of the invention, to such an extent that less deposit is accumulated in a week with the invention than in a single day without the invention. The resultant cleaner reflector surface increases the light intensity and lessens the heating of the reflector.

An important feature of the invention is the simple and rugged construction of my attachment whereby it is reliable in operation and gives long service without undue maintenance expense and trouble.

In the drawing:

20 Fig. 1 is a side elevational view with portions broken away of a reflector type projection arc lamp incorporating a water cooled attachment in accordance with the present invention;

25 Fig. 2 is a plan view of the attachment, the view being taken in the plane II—II of Fig. 1;

Fig. 3 is a rear elevational view of the attachment showing a portion of the projector in section, the view being taken in the plane III—III of Fig. 1;

30 Fig. 4 is a detailed vertical sectional view taken in the plane IV—IV of Fig. 3;

Fig. 5 and 6 are cross sections taken in the planes V—V and VI—VI respectively of Fig. 4; and

35 Fig. 7 shows the relative shapes of a copper coated carbon after being used in a lamp not equipped with the invention, a copper coated carbon after being used with the invention, and an uncoated carbon after being used with the invention.

40 Referring first to Fig. 1 there is shown a conventional lamp housing 10 positioned back of a projector 11. Near the rear (left) end of the housing 10, is a concave mirror 12 which is axially aligned with the optical system of the projector 11. Positioned in the optical axis are the negative carbon 13 and the positive carbon 14 between which the arc is formed. The carbons are longitudinally supported and fed by the conventional

45 carriages, only the carriage 16 for the positive carbon 14 appearing in Fig. 1. As these projectors are ordinarily used, carriage 16 not only physically supports the carbon 14 but also supplies the current thereto.

50 55 In accordance with the present invention, a

water cooling attachment 18 is provided which engages the positive carbon 14 adjacent its tip, cools the carbon, and constitutes the current connection thereto.

The carriage 16, and a corresponding carriage for the negative carbon 13, are usually motor driven to automatically feed the carbons as they burn away, and they still perform this function when my water cooling attachment 18 is employed. However, since automatic feeding mechanisms are well known in the art and do not constitute a part of the present invention, no feeding mechanism is described herein.

Referring to Fig 4, the water cooling attachment of the invention comprises an annular water jacket 20 having a central passage 21 of somewhat larger diameter than the positive carbon 14, and defining a water chamber 22 through which cooling water is circulated. This water may be conducted into the chamber 22 through a conduit 24 and exhausted from the chamber through a conduit 25. For convenience, the conduits 24 and 25 may extend into a header block 26 to which copper tube connections may be made to any suitable source of supply and exhaust. The water jacket 20 is supported in a ring 27 in which it may be locked as by a pair of set screws 28. The ring 27 is mounted on the upper end of an integral rod 29, the latter being locked by set screws 30 (Fig. 6) to a member 30 which in turn has a ball surface thereon which engages with a socket 31 in the upper end of a bracket 32, the member 30 being adapted to be clamped in the socket in the bracket 32 by a screw 33. The lower end of the bracket 32 may be secured as by screws 34 to the end of the bed 35 of the lamp housing. The ball and socket connection between the water jacket 20 and the bracket 32 permits accurate alignment of the water jacket with respect to the positive carbon 14 which it surrounds.

To facilitate heat transfer from the carbon 14 to the water jacket, and for other purposes to be described, there is provided an annular heat transfer bushing 36 which is screw threaded into screw threads 37 provided for that purpose in the water jacket 20 at the front end of the central passage 21 therein. By virtue of its threaded connection to the water jacket, the bushing 36 is in very good thermal conductive relation thereto, and it is accurately dimensioned as to its bore 38 so that its fits the carbon 14 sufficiently closely to be in very good thermal conductive relation thereto. Because of the fact that carbon is a relatively poor heat conductor, most of the heat generated in the tip portion of the carbon 14 by the arc is transferred through the bushing 36 to the water jacket and conducted away by the circulation of water therethrough.

As is well known, the usual arc produced in a projector lamp of the type herein discussed, produces a relatively long flame or tail which if directed toward the mirror 12 may blacken or cause breakage of the latter. I have found that in accordance with the present invention a magnetic deflector for the tail of the arc can be conveniently incorporated in my water cooling attachment. This device consists of a U-shaped element 40 of paramagnetic material such as soft iron, the two arms of which are clamped against the front end 41 of the water jacket by a shoulder 42 on the bushing 36, this shoulder 42 being the rear face of an expanded head 44 formed on the forward end of the bushing. The enlarged

head 44 not only serves to anchor the U-shaped arc deflecting member 40 but also functions to absorb radiant heat from the arc and help to limit the total rise in temperature within the lamp housing. As shown in the drawing, the bow portion 40a of the U-shaped arc deflecting member is positioned at the top and the open ends 40b of the member are bent rearwardly. It is found that this particular configuration is most effective in some instances, but in other instances it is found best to leave the ends 40b straight and/or to orient the U-shaped member in some position other than the vertical. The best position for any particular lamp can be readily determined by experiment.

As previously indicated, in accordance with the present invention, current is transmitted to the positive carbon 14 adjacent the tip thereof through the water cooling attachment instead of through the usual carriage 16. Connection is made through contact means consisting of a pair of substantially semi-cylindrical brushes 47 and 48 that slidably grip the carbon 14, the brushes being pressed against the carbon by a helical tension spring 49 that is extended around the brushes. Electrical connection is preferably made to each of the brushes 47 and 48 by separate pigtail connections 50 which may be extended to the water connection block 26 which is grounded to the frame of the machine. The brushes 47 and 48 may be of copper or a mixture of copper and graphite, the latter having a lower coefficient of friction against a copper-coated carbon, and the former having a lower coefficient against an uncoated carbon.

To support the brushes 47 and 48 there are provided extending from the rear end of the water jacket 20 a pair of diametrically disposed extensions 52 and 53 which connect to and support at their rear end a disc member 54, the latter having a central aperture 55 through which the carbon 14 extends. The extensions 52 and 53 together with the rear face 57 of the water jacket and the front face 58 of the disc member define a pair of approximately semi-cylindrical brush slots dimensioned to slidably receive the brushes 47 and 48.

It is well recognized that the resistance of arc carbons is high, for which reason it has been customary to provide them with copper coatings to conduct the current. This copper coating burns away clean at the highly heated tips adjacent the arc in my system. However when my water cooling attachment is not employed the copper coating sometimes fuses into globules near the tips of the carbon which globules interfere with the production of a normal arc. The present system not only improves the operation with copper coated carbons but enables the use of uncoated carbons, which are cheaper. This is because the brushes 47 and 48 contact the carbons relatively close to the tips thereof and at a constant distance from the tips. The current flows through such a short length of the carbon that the voltage drop therein is relatively small and the water cooling prevents materially heating of the carbons by the power consumed in them.

The voltage drop in carbon 14 remains substantially constant at all times because the distance that the current flows through the carbon remains constant. This aids greatly in maintaining the uniformity of the arc.

It is found that the water cooling attachment contributes materially to the formation of

a better crater in the positive carbon 14. Specifically, the crater is deeper, larger in diameter, and remains more constant in shape during continuous operation. A deep crater is desirable because it reduces the size of the flame or tail rising from the arc. Changes in size of the crater are undesirable because they produce colors and flicker on the screen.

The use of the invention produces a flatter illumination on the screen than is obtainable with the same lamp without the water cooling. This appears to be due to the fact that the water cooling of the positive carbon adjacent the tip thereof increases the diameter of the luminous crater which constitutes the light source. Thus by comparison of carbon A and B in Fig. 7, it will be observed that the uncooled carbon A has a longer taper and smaller tip diameter than the water cooled carbon B. This is due to the fact that because carbon B is maintained at a lower temperature, there is less external combustion rearwardly of the tip. By the same token, the copper coating does not burn as far back on the water cooled carbon B as on the uncooled carbon A. Carbon C in Figure 7 is typical of the tip shape of an uncoated carbon that has been used with the water cooler of the invention. It will be observed that it approximates the tip shape of carbon B. Uncoated carbons can be used with perfect satisfaction with my water cooler, whereas it is impossible to use them with the conventional lamp because of the heat generated within the carbon itself by the passage of the current therethrough.

The water cooling attachment reduces the heat waves in the air within the lamp housing and thereby reduces variations in intensity of light on the screen.

Although I am unable to explain the phenomenon, I find that with the water cooling attachment of the invention a larger than normal carbon can be employed without increasing the current and without reducing the light, while markedly increasing the life of the carbon.

Thus tests were run on the same projector using an 8 millimeter coated carbon without water cooling as against a 9 millimeter uncoated carbon with the water cooler of the invention. In each case, the current was maintained at 70 amperes. Without the invention, the light intensity on the screen measured 7-10-7 (left side, center, and right side respectively) whereas with the invention it measured 8-11-8. Using the smaller, copper coated carbon without the invention, the rate of carbon consumption was 3 minutes 6 seconds per inch, as against 5 minutes 7 seconds for the larger uncoated carbon with the invention. The disparity in carbon cost is much greater, the cost per hour without the invention being 22 cents as against 12 cents with the invention. Tests made under identical conditions (employing the invention) with a 7 millimeter copper coated carbon and only 50 amperes gave light intensity on the screen of 8-10-8 (better than was obtained with an 8 millimeter carbon and 70 amperes without the invention) a rate of carbon consumption of 6 minutes 12 seconds per inch, and a cost per hour of only 9 cents.

Although for the purpose of explaining the

invention, a particular embodiment thereof has been shown and described, obvious modifications will occur to a person skilled in the art, and I do not desire to be limited to the exact details shown and described.

5 I claim:

1. An attachment for a projection arc lamp having positive and negative carbons, a frame, and means on said frame for feeding said carbons longitudinally into arcing relation, said attachment comprising: an annular water jacket dimensioned to surround one of said carbons; contact means including a plurality of contact elements between which said carbon is positioned and means slidably supporting at least one of said contact elements with respect to said water jacket for lateral movement into engagement with said carbon; spring means urging at least one of said contact elements against said carbon for producing electrical contact between said contact elements and said carbons; a bracket attachable to the lamp frame for supporting said water jacket in stationary relation to said frame and in alignment with said carbon adjacent the normal arcing position of the tip thereof; conduit means for conducting water to and from said water jacket; and electric leads for conducting current to said contact means independently of said water jacket.

2. An attachment according to claim 1 in which said contact means is positioned at the rear end of said water jacket remote from the carbon tip; and an annular heat transfer bushing of high thermal conductivity is mounted adjacent the front end of said water jacket in thermally conductive relation therewith and dimensioned to surround said carbon in more closely fitting relation than the water jacket.

3. An attachment according to claim 2 in which said heat transfer bushing is threaded into the front end of said water jacket.

4. An attachment according to claim 3 including a generally U-shaped arc-deflecting member of para-magnetic material held against the front end of said water jacket by said heat transfer bushing, the arms of the U straddling an intermediate portion of the bushing and lying against the front end of the water jacket, and the front end of the bushing extending in front of the water jacket and having an enlarged head defining a shoulder for clamping the arms of the U-shaped member against the water jacket.

5. An attachment according to claim 1 in which said means for slidably supporting said contact means comprises a pair of diametrically disposed rearwardly extending extensions on said water jacket, and a centrally apertured disc member supported by said extensions and defining therewith and the rear end of said water jacket a pair of substantially semi-cylindrical brush slots lying on opposite sides of said extensions; said contact means comprising a pair of substantially semi-cylindrical brushes positioned in said brush slots; and tension spring means encircling said brushes for retaining them in said slots and urging them against said carbon.
